UNITED STATES PATENT OFFICE.

ARNOLD STUCKI, OF ALLEGHENY, PENNSYLVANIA, ASSIGNOR TO PRESSED STEEL CAR COMPANY, OF PITTSBURG, PENNSYLVANIA, A CORPORATION OF NEW JERSEY.

STOCK-CAR.

SPECIFICATION forming part of Letters Patent No. 772,974, dated October 25, 1904.

Application filed October 24, 1902. Serial No. 128,641. (No model.)

To all whom it may concern:

Be it known that I, ARNOLD STUCKI, a citizen of the United States, residing at Allegheny, in the county of Allegheny and State of Pennsylvania, have invented a certain new and useful Improvement in Stock-Cars, (Case A,) of which the following is a full, clear, and exact description.

This invention has for its object to provide 10 a stock-car with a so-called steel "underframe" and to use metal in the construction of its sides in such way that the sides become, in effect, a truss, whereby the load strains and shocks are efficiently resisted.

15 In carrying out my invention I may use a steel underframe of any desired construction and composed of pressed shapes or structural shapes and combined with a body structure having metal side plates which are connected 20 with the side sills by diagonals arranged as tension members or, if desired, as compression members.

The invention comprises not only the foregoing construction, but certain details, all as 25 hereinafter more particularly set forth and finally claimed.

In the accompanying drawings, illustrating 30 my invention, in the several figures of which like parts are similarly designated, Figure 1 is a central vertical longitudinal section showing at the right-hand end also a partial elevation of the near side. Fig. 2 is a top plan view, the upper left-hand end being a section in a plane above the floor-stringers, the lower 35 left-hand portion being in a horizontal plane of the top of the side sills, center sills, and the transoms, the upper right-hand portion showing the floor at and adjacent to the door and the lower right-hand portion showing the 40 roof-planks, purlins, and carlines. Fig. 3 is an end elevation on the right-hand side and a vertical section on the left-hand side, the section being substantially in the plane of the door. Fig. 4 is a cross-section of the under- 45 frame, taken substantially in the plane of line A B, Fig. 2.

While it is to be understood that the invention is not limited to the use of any particular

material in the construction of the car and that where metal is used either special pressed shapes or commercial or structural shapes may be employed, still for the purpose of illustrating the principle of the invention the following description will be confined to a structure in which the metallic parts are of pressed steel—that is to say, they are parts pressed to shape—unless otherwise specifically mentioned.

The underframe has side sills 1 of channel form and of uniform width throughout, while the center sills 2 are of the well-known belled and flanged construction. The end sills 3 are as usual and connected with the side sills and center sills. The bolsters are composed of pairs of flanged diaphragms 4, arranged between the side sills and the center sills, and similar flanged diaphragms 5, arranged between the center sills, a top cover-plate 6, and a bottom cover-plate 7, the cover-plates being riveted to the flanges of the diaphragms. The 70 ends of the bolsters between the diaphragms 4 may be reinforced by diaphragms or plates 8, riveted to the said diaphragms and to the side sills. At intervals throughout the length of the car there are diaphragms 9 between the 75 side sills and center sills and diaphragms 10 between the center sills, constructed with flanges all around and riveted in place and constituting transoms. The draft-rigging portions 11 may be of any approved construc- 80 tion.

Instead of using a built-up bolster with center sills running continuously from end sill to end sill I may use continuous bolsters with independent center sills and draft-rigging sills, 85 or any other well-known constructions of underframe may be substituted for that herein described, although for purposes presently appearing it will be seen that the underframe described is the one possessing greatest advantages in connection with the present invention.

Whether the side sills be of pressed shapes or structural metal they constitute the lower chords or tension members of trusses whose 95 upper chords or compression members are

metal side plates 12, erected at the top of the 5 car, beneath the roof, and connected with the side sills by means of diagonal tension-straps 13 and vertical posts 14, 15, and 16, secured, preferably by riveting, to the said side sills and diaphragms and the side plates. The depth of each truss is the height of the side of the car.

Each center sill forms a girder of nearly 10 uniform strength, while the side sills are not designed to serve as girders, but simply, as already stated, as the bottom chords of deep trusses. The several cross diaphragms or 15 transoms constitute connections between the center sills and the side sills, so as to make the center sills work in harmony with the side trusses, and if the side trusses be stronger and stiffer than the center sills the various diaphragms will serve to transmit part of the load 20 from the center of the car to the sides, and vice versa.

The corner-posts 14 are angles, as are the door-posts 15, while the intermediate posts 16 are T's, and the door-posts and intermediate 25 posts are extended to the underframe and riveted to the diaphragms 9, while the posts adjacent to the bolsters are riveted to the diaphragms 8. By this construction the diaphragms form a rigid connection for the different posts, thus giving the car rigidity by holding the posts not only together, but also preventing them from letting the car get out of square in cross-section. These posts not 30 only reduce the bulkiness of the car, but they also render the car very stiff and prevent bulging out when stock or lading presses from inside. The posts may be rolled or pressed, and angles or other sections instead of T's may be used.

40 The diagonals 13 are formed as tension members in order to get the strength with very much less material than if they were used as compression members; but of course compression members could be substituted, and 45 in that case it would be better to use pressed shapes of greatest cross-section centrally, so as to prevent buckling when the load comes upon them.

The side plate 12, as shown more particularly in Fig. 3, is an angle rolled or pressed, with its flange extending outwardly to form a continuous support for the side purlin 17.

The carlines 18 are of pressed steel, by preference, of U shape in cross-section, as seen in 55 Fig. 1, with pockets 19 to receive the purlins 20, and these carlines are provided with flanges 21, which are riveted to the side plates 12. The end plates 22 are also of pressed steel, and, as shown in Fig. 3, they are provided 60 with pockets 23 to receive the ends of the purlins. These purlins project beyond the end plates, so as to support the roof nearly to the end.

The doors 24 may be of any approved con-

struction, as also may be other parts of the 65 car shown and not specifically described.

The ends of the car may be provided with vertical T-posts 25 and diagonals 26, both of which may be riveted at opposite ends to the end plates and some portion of the under- 70 frame—as, for example, the flange 27, rising from the end sills, as indicated in Fig. 3.

As seen in Fig. 2, there are provided angle-reinforces 28, riveted to the side sills and door-posts, and the adjacent diaphragms are 75 also provided with similar angle-reinforces 29, riveted to them and the side sills, so as to get additional strength near the center of the car, where it is needed most. The slats on the inside are preferably bolted to the posts by 80 means of carriage-bolts.

By the construction described a very stiff underframe and also a very stiff superstructure are provided, well adapted for stock-cars, although the invention is not limited to 85 its use in connection with stock-cars.

Instead of the diagonals herein shown I 90 may use rods, as set forth in my concurrent case, or other forms may be substituted.

What I claim is—

1. A car, having side sills of uniform cross-section throughout, bellied center sills, flanged diaphragms connecting the side sills and center sills and riveted to both, and other diaphragms interposed between and riveted to 95 the center sills, end sills also riveted to and connecting the side sills and center sills, the side sills serving as lower chords of trusses, side plates forming upper chords of trusses, T-bar vertical posts, and diagonals, said posts 100 and diagonals riveted directly to the said top and bottom chords.

2. A car, having an underframe provided with side sills serving as the lower chords of trusses, diaphragms connecting the side sills 105 transversely, side plates forming the upper chords of the trusses, vertical T-bar posts riveted to the side sills and diaphragms, and also riveted to the side plates, and diagonals interposed and riveted to the side sills and the side 110 plates.

3. In combination with the sides of a car, side plates having outwardly-turned flanges, carlines having end flanges riveted to said side plates, end plates, and purlins mounted 115 upon the flanges of the side plates and upon the carlines and end plates.

4. In combination with the side sills, door-posts and the central diaphragms, reinforcing angles riveted to the door-posts and diaphragms respectively and to the side sills.

In testimony whereof I have hereunto set my hand this 20th day of August, A. D. 1902.

ARNOLD STUCKI.

Witnesses:

A. F. SMELTZER,
J. A. LANGFITT.

It is hereby certified that in Letters Patent No. 772,974, granted October 25, 1904, upon the application of Arnold Stucki, of Allegheny, Pennsylvania, for an improvement in "Stock-Cars," an error appears in the printed specification requiring correction, as follows: In line 2, page 2, the word "sar" should read *car*; and that the said Letters Patent should be read with this correction therein that the same may conform to the record of the case in the Patent Office.

Signed and sealed this 8th day of November, A. D., 1904.

[SEAL.]

F. I. ALLEN,
Commissioner of Patents.
